waltung und Verwertung von gewerblichen
Schutzrechten mit beschränkter Haftung, Ber-
lin, Germany, a corporation of Germany

Application July 31, 1939, Serial No. 287,517
In Germany August 8, 1938

7 Claims. (Cl. 179—18)

The present invention relates to telephone systems with main and sub-exchanges in which the sub-exchanges not provided with battery feeding arrangements are connected with the main exchange over a number of junctions. More particularly it relates to arrangements for providing busy indication of subscribers' lines at such a sub-exchange.

In known arrangements with a number of junctions between main and sub-exchange indication that a subscriber's line is engaged is easily given since the sub-exchanges are provided with local battery feed so that the engaged subscriber's line can be guarded, in the manner usual in selector systems, over a special auxiliary conductor in a local circuit of the sub-exchange. Difficulties occur when the sub-exchange has no battery.

The present invention relates to a method of solving the problem of connecting sub-exchanges not provided with battery feed with the main exchange over a number of two-conductor junctions and of connecting a calling sub-exchange subscriber to a free junction line. This result is obtained in that, in the sub-exchange, switching arrangements are associated with each subscriber which, on a call from a subscriber, are so controlled from the main exchange over one of the junction lines corresponding to the junction to be used for setting up the connection, that the calling subscriber has access only to the main exchange over this junction.

The invention is illustrated with respect to an embodiment shown in Figs. 1 and 2, Fig. 2 being a continuation of the system to the right of Fig. 1, in which a telephone installation including a sub-exchange UA without local battery feed is connected to a main exchange HA over two lines (VLI, VLII).

For connecting a sub-exchange subscriber to the junction extending to the main exchange a selector is provided at each junction in the sub-exchange which selector is set by impulses transmitted from the main exchange and each subscriber is also associated with a relay for each junction. For outgoing calls one junction (VLI) has prior facilities and for incoming calls the other junction line (VLII) has prior facilities.

In the main exchange, a switch mechanism (wiper *mw*) is provided for each junction which switch means are positioned synchronously with the sub-exchange selector when impulses are transmitted for setting the sub-exchange selector. For outgoing and incoming connections it serves to indicate that the calling sub-exchange subscriber's line is engaged and, moreover, for out-

going connections it switches in the calling subscriber's meter at the main exchange.

For testing the condition of the subscriber's line at the main exchange, testing arrangements are associated with each junction and are connected to the wipers of the previously mentioned switch in which both contacts corresponding to the individual sub-exchange subscribers in the contact banks of the switches for both lines are connected together. When indication is given that a subscriber's line is engaged at the switch of one junction line the testing apparatus at the switch of the other junction line is seized when the same subscriber has been selected.

15 In the embodiment the setting up of the connections of the telephone system takes place in the following manner:

In the normal condition of the system a permanent current circuit is completed over each junction and prepares call circuits over each junction for all the subscribers of the sub-exchange UA. The permanent current circuit over the junction line VLI extends over: earth, battery, winding 1 of relay X1, contacts 43x1, 42y, 41a, 34k, wiper *mw1* in zero position, *a*-conductor of the junction line VLI, contact 13dw1 or contact 14u1 and wiper *w11* in zero position, wiper *w12* in zero position, contact 11m12, relays M11, M12, earth. In this circuit relays M11 and M12 are energised so that 20 their contacts are in the position shown. Therefore a multiplied call circuit for all subscribers of the sub-exchange UA is prepared over the junction VLI to the main exchange HA.

The permanent current circuit over the junction line VLII extends in a corresponding manner over the *a*-conductor of this junction so that, in the sub-exchange, the relays M21 and M22 of the junction line VLII are energised. These relays have their contacts in the positions shown 25 so that over the junction VLII a multiply-connected call circuit is prepared for all subscribers of the sub-exchange UA. By means of the relays (e. g. A2, B2) associated with subscribers of each junction the two multiply-connected call 30 circuits corresponding to the two junctions are made accessible to all subscribers of the sub-exchange UA. In the embodiment the arrangement is such that on a call from a subscriber when both junction lines are free, a call circuit is first 35 completed over the junction line VLI in that the relay X2 of the junction line VLII for receiving the call impulse is short-circuited over contact 104b of the relay B of the junction line VLI so that it cannot be operated by the call and only 40 the relay X1 can be energised. This circuit, when 45

for example the subscriber $Tn2$ is the calling subscriber, extends over: earth, battery, winding I of relay $X1$, contacts $43x1$, $42y$, $41a$, $34k$, wiper $mw1$ in zero position, a-conductor of the junction line VLI , contact $13dw1$ or contact $14u1$ and wiper $w11$ in zero position, wiper $w12$ in zero position, contacts $9dw1$, $8m11$, resistance $W11$, contact $1b2$, subscriber $Tn2$, contacts $84b2$, and $6a2$ or $87a2$ and $89b2$, earth. The relay $X1$ by closing contact $59x1$ locks its winding II over the resistance $W113$ in a circuit which after the switch is stepped on extends over wiper $mw2$, contacts $57x1$, $51p1$, (or, later, $52v$), and the resistance $W112$. Contact $43x1$ operates when relay $X1$ is energised and breaks the permanent current circuit extending over the a-conductor of the junction line VLI so that, in the sub-exchange UA , the relays $M11$ and $M12$ are disconnected. These two relays allow their operated contacts $1m12$, $8m11$ and $11m12$ to open interrupting the multiply-connected call circuit in the sub-exchange and the permanent current circuit while the rotary magnet $Dw1$ of the selector in the sub-exchange UA is connected to the b-conductor of the junction VLI by the closing of contact $17m11$ and thus the following circuit is completed: earth, battery, winding I of relay K , contacts $68y$, wiper $mw3$ in zero position, contact $55q$, b-conductor of the junction line VLI , contacts $18u1$, $17m11$, rotary magnet $Dw1$, earth. In this circuit relay K and rotary magnet $Dw1$ are energised. Winding I of relay A is connected to the a-conductor of the junction line VLI by the closing of contact $35k$ so that, after the selector in the sub-exchange is stepped-on by the rotary magnet $Dw1$ energising over the contact $12dw1$ which is operated by the rotary magnet $Dw1$, the following circuit is completed: earth, battery, winding I of relay A , contacts $40z$, $39a$, $38y$, $33x1$, $35k$, wiper $mw1$ in zero position, a-conductor of the junction line VLI , contact $12dw1$, wiper $w13$ on the segment $1-6$, resistance $W15$, earth. In this circuit relay A is energised so that contact $43a$ closes and causes the rotary magnet Dmw of the switch in the main exchange to energise over: earth, battery, rotary magnet Dmw , contacts $47q$, $48a$, $50b$, $49p1$, earth. The switch mechanism in the main exchange is advanced by one step. Relay Y is energised over its winding I by the closing of contact $31dmw$ so that as contact $68y$ is opened the winding I of relay K is disconnected. The circuit extending over the b-conductor of the junction VLI for the rotary magnet $Dw1$ is interrupted after the stepping-on of the switch at the main exchange at wiper $mw3$, so that the circuit completed for the winding I of relay A over the a-conductor of the junction VLI is disconnected by the opening of contact $12dw1$. Relay A is thus disconnected and breaks the circuit of the rotary magnet Dmw at contact $48a$ so since contact $31dmw$ is opened the relay Y restores.

During the period during which relay Y is energised relay K is not energised, the test circuit for determining the calling subscriber is prepared in that battery potential is connected to the a-conductor over the resistance $W111$ and contact $37y$ and earth potential is connected to the b-conductor over the contact $61k$ and the test relay B . By means of the battery potential on the a-conductor in the sub-exchange relay $A1$, connected over wiper $w11$ of the subscriber $Tn1$ (not shown), is energised in order to determine whether this subscriber is the calling subscriber. If the subscriber (not shown), is already connected to the junction line VLI then, since his

relay $B1$ is energised, an energisation of relay $A1$ is prevented so that the subscriber's conversation over the other junction line is not disturbed.

Since, in the present case, the subscriber $Tn2$ makes a call, after the switch is first stepped-on there is still no test circuit completed and after the energisation of relay Y , and the closing of contact $68y$, the winding I of relay K , is energised again over: earth, battery, winding I of relay K , contact $60y$, resistance $W120$, contacts $54b$, $53v$, wiper $mw2$ on segment $1-5$, earth. The relay K over its contact $28k$ connects battery to the b-conductor. The interaction described above is repeated so that in the sub-exchange the selector is advanced by a further step and by sending back an impulse over the a-conductor of the junction VLI the relay A in the main exchange HA is energised and thus the switch in the main exchange is also advanced by a further step. After the second step relay $A2$ is energised as long as relay Y is energised over: earth, battery, resistance $W11$, contacts $37y$, $33x1$, wiper $mw1$ on segment $1-6$, a-conductor of the junction line VLI , contact $14u1$, wiper $w11$ on contact 2 , winding I of relay $A2$, contact $15b2$, earth. The relay $A2$ disconnects the calling subscriber $Tn2$ from the junction VLI . Moreover, the calling subscriber is connected over contact $3a2$ with a branch, used for all subscribers, multiplied to the a-conductor at which branch a condenser is connected for bridging over the A-relay, while at contact $86a2$ a corresponding connection is effective for bridging over the relay $U1$ at the b-conductor. In this special arrangement two condensers only are used for bridging over the relays at each conductor for all the subscribers.

After these operations, taking place over the subscriber's loop the following circuit is completed: earth, battery, resistance $W111$, contacts $37y$, $33x1$, wiper $mw1$ on segment $1-6$, a-conductor of the junction line VLI , contact $13dw1$, wiper $w12$, on the contact 2 , winding II of relay $A2$, contact $1b2$, subscriber $Tn2$, contacts $84b2$, $5a2$, relay $U1$, contact $19u1$, earth. In this circuit relay $A2$ remains energised while relay $U1$ is energised so that, with disconnection of earth at contact $19u1$ and of the rotary magnet $Dw1$ at contact $18u1$, the b-conductor of the junction line VLI between the calling subscriber $Tn2$ and the main exchange HA is switched through over the contact $20u1$. Over the calling subscriber's loop the relay B , connected to the b-conductor of the junction line VLI , is now energised in series with relays $U1$ and $A2$ since contact $61k$ is closed. By the opening of contact $50b$ a further energisation of the rotary magnet Dmw is prevented. Relay Y now restores and in place of the resistance $W111$ connects the relay A to the a-conductor so that now this relay is energised in series with the relays $A2$, $U1$ and B .

Meanwhile, by the closing of contact $69b$, the relay $R1$ is energised over the choke $D1$ for the purpose of starting-up the pre-selector $VW1$. Further, contact $63b$ closes connecting the winding I of relay V so that, contact $111v$ closing, the following circuit is completed (1): earth, battery, windings I and II of relay $P1$, contacts $110y$, $111v$, wiper $mw5$ on contact 2 , resistance $W19$, earth. At contact $109p1$ the high resistance winding II of relay $P1$ is short-circuited so that at the main exchange the calling subscriber's line is indicated as being busy. Should the subscriber $Tn2$ now be called over the junction line VLI according to the positioning of the wiper $mw5$ (II), in the manner explained later, the relay

P2 is not energised. As a result earth potential (compare VLI: earth, W15, 81p1) is not connected over a p2-contact to the b-conductor of the junction line VLII to the series final selector, as can be seen in the case of the junction VLI, whereby a relay operated up till the reply of the required subscriber of the b-conductor of the final selector is restored and on transmission of an engaged signal from the final selector the test conductor c of the junction line of the sub-exchange is disconnected so that this junction line is released. A further connection to the subscriber already engaged is thus prevented. It can be seen that in the main exchange HA the line of the calling sub-exchange subscriber Tn2 is marked as being engaged by means of the relay P1 so that connections over the other line cannot be put through to him.

If, in the meanwhile, the pre-selector VW1 started up by the call impulse, has found a free selector, then, in known manner, the relay T1 is energised whereby the calling subscriber is switched through over the wipers of the pre-selector VW1 to the numerical impulse receiver. When the subscriber Tn2 operates his dial switch the relays A and B are restored intermittently by interruption of the subscriber's loop so that by the corresponding interruption of the contact 69b a transfer of impulses for setting the subsequent numerical impulse receiver occurs. When the required subscriber has been reached after transmission of the necessary impulse trains, there follows transmission of ringing current. When he replies, the ringing current is disconnected in the known manner and a metering impulse is transmitted over the test conductor by which the winding I of relay Z is operated. By the closing of contact 1152 the meter Z2 corresponding to the calling subscriber Tn2 and connected to contact 2 over the wiper mw6 of the switch in the main exchange, is operated.

When the calling subscriber hangs up at the end of a conversation the relays A and B and, a short while later, relays A2 and U1 are restored by the interruption of the subscriber's loop. By the opening of contact 69b the numerical impulse receiver is released as well as the preselector VW1 which, over its wiper c, after it has restored to normal, short-circuits the winding II of relay V which after the disconnection of winding I has hitherto remained energised over contact 76v. The holding circuit of winding II of relay X1 is interrupted by the opening of contact 52v so that, during the following return movement of the selector in the sub-exchange, a testing by a calling subscriber is prevented by means of the relay B (contact 62x1 open). After the release of relay V and on the opening of contact 111v relay P1 is also disconnected. By the closing of contact 53v winding I of relay K is further energised so that now the stepping-on of the sub-exchange selector which is of not further interest, and of the switch in the main exchange to their normal positions, takes place. When the sub-exchange selector has taken its final step, as long as the rotary magnet Dw1 is still energised, relays M11 and M12 are energised over contact 10dw1 over the a-conductor of the junction line VLI and resistance W10 and over the winding I of relay X1 so that when contact 11m12 closes after the disconnection of rotary magnet Dw1 the permanent current circuit (already indicated) for the multiple connection of the call circuits is closed.

As described above the relay B in the main ex-

change is energised during the existence of a connection over the junction line VLI so that at the junction line by the opening of contact 104b the short circuit for winding I or relay X2 is removed. As a result a further call for setting up an outgoing connection from the junction line VLII can be undertaken in one of the ways described above in connection with the junction line VLI. The switching arrangements of the junction line VLII, not shown in the drawings, operate in the same manner as those explained for the junction line VLI. The connected subscriber's line is locked by means of the relay P2 over the wiper mw5 (II).

If instead of an outgoing connection an incoming connection is set up then the final selector LW is first set by means of the characteristic digit of the sub-exchange UA. The final selector LW then tests which line is free in known manner, it then tests, therefore, the next junction line VLII since this is the first line connected in its contact bank. If this line is engaged it steps on to the junction line VLI. When this is free the relays Z, Y and T1 are energised over the c-wiper of the final selector LW. Over the b-conductor the relay K (winding II) is energised, from the series final selector LW. The other switching operations (energising of relays Q, V, X1) are performed after the rotary magnet Dw1 has been connected to the b-conductor by the interruption of the permanent current circuit over the a-conductor (42y) by the relay K operated by the impulses transmitted over the b-conductor; this switch (44k) in the main exchange and the selector (27k) in the hub-exchange are stepped on in synchronism. In the main exchange when these have been set, the relay P1 tests to determine if the required subscriber marked by the positioning of the wiper mw5 in the main exchange is free. Should this be the case, relay P1 operates and after disconnecting the winding II of relay K (Y restores after the impulse transmission) over the contact 81p1, earth is connected to the b-conductor of the final selector so that a call is initiated. The required subscriber is connected by the operation of the corresponding A-relay over the wiper w11 after the selector in the sub-exchange has been set in position. At contact 56p1 relay B is connected to the b-conductor.

When the required subscriber replies the relays A, U1, B operate over the subscriber's loop in series with the already energised A-relay of the required subscriber. The disconnection of ringing current in the final selector is brought about by the opening of contact 80b. Further operations are not of interest.

It should be noted that all switching operations described for the junction VLI in the setting-up of outgoing or incoming connections are performed in the manner when using the junction VLII.

I claim:

1. In a telephone system having main and sub-exchanges and two conductor trunk lines connecting said exchanges, means in the main exchange for supplying all battery feed to the sub-exchanges, subscribers' lines in the sub-exchange normally common to a plurality of said trunk lines, step by step switching devices on each trunk line, means operated by the initiation of a call on a subscriber's line for operating the switching devices of one trunk line to complete a connection from the subscriber's line over the trunk line to the main exchange, one of the switching devices on each trunk line located in the main

exchange and operating to prevent a connection being set up to the calling subscribers over other trunk lines.

2. A telephone system as claimed in claim 1 wherein the switching device of a trunk line in the main exchange is operated in a manner distinctive of the calling line.

3. In a telephone system having a plurality of trunk lines connecting a sub-exchange to a main exchange, subscribers' lines in the sub-exchange normally connected to a plurality of said trunk lines, a switching arrangement in the main exchange for each trunk line operated when a call is extended either to or from a line in the sub-exchange, said arrangement always operated in a manner distinctively associated with the line in the sub-exchange to or from which the call is extended.

4. In a telephone system having main and sub-exchanges with trunk lines interconnecting them, means for supplying all battery feed to the sub-exchange over said trunk lines, subscribers' lines in the sub-exchange, a common circuit including all of said lines and said trunk lines, said circuit controlled from any line to extend a connection over one of said trunk lines, switching devices in the main exchange for each trunk line and

operated thereover under control of said common circuit to mark the line calling as busy.

5. A telephone system as claimed in claim 4 wherein there is also means for operating said switching devices whenever a call is extended from the main exchange to a subscriber's line in the sub-exchange.

6. A telephone system as claimed in claim 4 wherein there are also switching devices for each trunk line in the sub-exchange and means whereby the switching devices of each trunk are operated in synchronism.

7. In a telephone system, a main and a sub-exchange, two conductor trunk lines connecting said exchanges, a step by step switch for each trunk line located in the main exchange, means for operating one of said switches either on calls to or from the main exchange when the associated trunk line is used, said switch always operated in a distinctive manner dependent on the line in the sub-exchange included in the call, means controlled by each switch for marking the associated line in the sub-exchange busy and testing means controlled over said switch for testing the condition of lines in the sub-exchange.

HELMUT POST.
